CHEST OR THE LIKE

Steven E. Mautner, Port Jervis, N. Y., assignor to
Skydyne, Inc., Port Jervis, N. Y., a corporation
of New York

Application August 7, 1945, Serial No. 609,439

1 Claim. (Cl. 217—65)

1

This invention relates to improvements in enclosures such as rooms, cabinets and chests and which for convenience will be referred to herein simply as chests and more particularly to the provision of chests adapted to withstand service under adverse conditions due to climate, subjected to the action of liquids, vapors and gases, and electricity, and to handling in shipping and storing.

An important object of the invention is to provide a novel and advantageous chest.

Another object is to provide a chest comprising panels supported by an improved frame by which the panels are supported in an improved manner against both inward and outward pressure.

Yet another object is to provide an improved chest of the character described in which the panels provide effective heat insulation and electric shielding.

Still another object of the invention is to provide an improved chest which is fungus proof and insect proof.

A further object of the invention is to provide novel skids at the top and bottom of each chest whereby waste space between chests in a vertical column will be eliminated and accidental relative movement in a lateral direction will be prevented.

Other objects, features and advantages will appear upon consideration of the following detailed description and of the drawings, in which

Fig. 1 is a perspective view of a chest constituting one embodiment of the present invention;

Fig. 2 is an exploded view of the chest including perspective views of the various parts in separated relation but in such relative positions as to indicate the manner of assembling the same;

Fig. 3 is a section taken along the line 3—3 of Fig. 1;

Fig. 4 is a section taken along the line 4—4 of Fig. 1;

Fig. 5 is a section taken along the line 5—5 of Fig. 2;

Fig. 6 is a top plan view of a chest according to the present invention illustrating the arrangement of skids at the top and bottom thereof; and

Fig. 7 is a section taken along the line 7—7 of Fig. 6.

Referring to the drawings, there is illustrated a chest which may be considered as built up on a flat bottom or bottom panel 10 of which the edges fit into horizontal grooves 11 in the lower parts of frame members 12 provided also with vertical grooves 13 receiving respectively the lower edges of a front or front panel 14, a back or back panel

2

15, and sides or side panels 16. At the upright edges of the chest are similar frame members or posts 12 having grooves 11 receiving the side edges of the front and rear panels or walls 14 and 15 and grooves 13 receiving the vertical edges of the side or end panels 16. The frame members 12 at the bottom and upright edges are shaped at their ends, as by mitering, to fit together at the bottom corners of the chest and the ends thus brought together are covered and reinforced by suitable metal corners 17 which may be square or very slightly rounded.

The frame members 12 are in the form of angles with the grooves 11 and 12 in the flanges thereof, the grooves 11 being deeper than the grooves 13 and extending across the inner edges thereof but separated therefrom by connecting webs 17a. This construction of the frame members serves to provide strong support of the various panels against either inward or outward pressure. These frame members or angles 12 may be formed by extrusion and may be of metal resistant to corrosion. For example, angles 12 and corners 17 may be made of aluminum or of an aluminum alloy. At both ends of each frame member 12 of the bottom and at the lower ends of the vertical frame members, the flanges may be cut away with a mitered cut so as to fit together and furnish well formed corners over which the metal corners 17 will fit.

The bottom panel 10 and the upright walls or panels 14, 15 and 16 are preferably of material such as veneer, plywood boards or the like 18 with the parallel faces thereof covered by sheet material of metal or non-metallic material 19 and which may be of aluminum which protects the wood from moisture, vapors, etc. which might cause damage thereto. If the upper edges of the vertical walls or panels were the same as the other edges thereof, the plywood would be exposed when the chest is open and subjected to conditions tending to damage the plywood. To avoid this difficulty the sheet material 19 is carried over the upper edge of the plywood of each vertical panel, and for that matter the outer and inner faces of the panels might be covered by one continuous sheet bent over the top edge. If desired, some or all of the edges of other panels may be covered with suitable material such as aluminum.

To obtain suitable insulation against heat transfer the core may be made of balsa wood which is light and strong and has good heat-insulating qualities. The frame members 12 and corners 17 may be secured to each other and to

the metal-covered plywood boards or plates 18 by means of fastening devices 20 passing through the walls of the grooves 11 and 13 and the edges of the plywood boards or walls 18 and secured as by adhesive or by riveting. The sheet material itself is secured to the veneer or plywood panels as by means of adhesives or other bonding material.

The chest is provided with a cover 21 which may be either set on or removed from the top of the chest proper. This cover comprises a panel 22 of plywood covered by sheet metal 19 such as aluminum and having its edges fitting into deep grooves 11a in frame members 12a which have wide downwardly facing grooves 13a to receive not only the upper edges of the upright panels but the upper ends of the posts 12 connecting the vertical panels. The grooves 13a are provided with a resilient gasket 23 of suitable material such as rubber, enabling a tight seal to be effected between the cover and the upper edges of the upright walls or panels. At the corners of the cover the frame members 12a may be mitered to provide good corners and these corners may be covered by suitable metal corner members 17.

It will be evident that mere insertion of the edge of a panel in a groove of a frame member would not produce a seal against gases, liquids or vapors. An effective seal at such parts may be effected by inserting sealing material 24 between the edge portions of the panel and the inner surfaces of the corresponding grooves, as best shown in Fig. 4.

To draw the cover 21 down and press the gasket 23 tightly against the top edges of the upright walls or panels, each frame member 12a is provided with a short metal strap 25 having at its free end an aperture 26 to receive the hook 27 of any suitable tightening device 28 which may be operated to tighten or open the clamp by swinging a lever 29 down or up.

For convenient handling of the chest, the side panels 16 may be provided with handles 30.

As illustrated in Figs. 6 and 7, another feature of the invention relates to novel skids 31 applied to the tops and bottoms of the chests in a novel manner to economize space and to effect interlocking between skids on successive chests in a column and thereby prevent a chest from accidental displacement from the top of the next chest below which might at least result in a fall of the upper chest and damage to the chest or other objects, or to persons.

As illustrated the frame members 12 at the bottom of the chest and the frame members 12a of the cover thereof project to substantially the same extent beyond the outer surfaces of the panels 10 and 22 and the corners 17 and straps 25 may project beyond the frame members. The straps 25 are found only on the cover and sufficient space for them is provided due to engagement between the corners on the top of one chest and the bottom of the next higher chest. The skids may be of such thickness as to fit between the adjacent panels of two chests of which one is piled on the other; that is, the skids may be of a thickness substantially equal to the sum of the projections of the corners 17 beyond the panels.

The skids are preferably of metal, such as aluminum, and are arranged on the tops and bottoms of the chests so as to cooperate and prevent relative lateral movement. A preferred arrangement is that shown in Figs. 6 and 7, in which there are four parallel rectangular skids 31 ar-

ranged in pairs near opposite ends of the cover 21, all of the skids being preferably parallel to one edge of the cover. The skids of each pair may be offset and preferably to such an extent that they are just out of either longitudinal or transverse overlapping relation. On the bottom panel of the chest, the displacement of the skids 31 is reversed, and when one chest of this kind is correctly set on another each skid of either upper or lower set will enter a corresponding angular space of the other set and assure not only correct positioning but prevent relative lateral movement between adjacent chests in a pile thereof. Obviously, the arrangement of the skids may be varied in many ways.

It will be obvious that chests constructed according to the present invention will have many advantages over prior forms of chests. For example, the frame of the chest is such as to impart strength thereto and to furnish effective support to the panels against inward or outward pressure. The interior of the panels is of such character as to resist transfer of heat and cold, to assist in producing a light weight but strong chest, and to assist in damping vibration. The feature of covering the plywood panels with metal sheet material serves not only to protect the surface of the panel but also to shield the chest against electrical action. The special form of the cover tends when closed to hold in position the sides of the chest and thus assure a stronger chest, and makes for a better closing because the rubber gasket is held definitely in place. The fitting together of the panels and the frame members in both the body of the chest and the cover and the use of sealing material in the grooves of the frame members tend to render the chest vapor proof, moisture proof, waterproof, fungus proof and insect proof.

It should be understood that various changes may be made and that certain features may be used without others, without departing from the true spirit and scope of the invention.

I claim:

45 A chest or the like having a top panel and a bottom panel, framing means for holding the edges of said panels and projecting from the outer surfaces of said panels, whereby said panels will be depressed below the edge framing means and when one chest is stacked on top of another the framing means of the bottom chest will be contacted by the framing means of the top chest so that the top chest will be supported on the framing means of the bottom chest and there is a substantial space between the top of the lower chest and the bottom of the top chest, skid means for holding the chests against sliding comprising a pair of elongated blocks secured to the top panel of the bottom chest, said blocks being arranged 50 substantially parallel to each other in offset relation and corners adjacent each other so that there are two pairs of right angular arranged abutment faces, corresponding faces being generally in line with each other and the two pairs of faces being 55 generally at right angles to each other, the bottom of a chest to rest on the bottom chest having a corresponding pair of blocks arranged as aforesaid and on the bottom of the top chest and positioned to engage corresponding abutment faces of the first mentioned blocks, a second set of blocks 60 on the bottom and top panels and spaced from the other blocks and arranged the same as the first set of blocks, whereby the abutment surfaces on each pair of blocks on the bottom panel will 65 contact adjacent surfaces on the corresponding 70 75

blocks of the top panel so as to hold said chests against sliding off in any direction, all of said blocks being of a thickness to fit between said top and bottom panels so that the top chest is carried by the frame means of the lower chest and not by the top panel thereof.

STEVEN E. MAUTNER.
